DESIGN FOR A COMBINED SHAWL AND HEAD COVERING

Raymond M. Wolfe, Louisville, Ky.

Application July 21, 1942, Serial No. 107,633

Term of patent 3½ years

To all whom it may concern:

Be it known that I, Raymond M. Wolfe, a citizen of the United States of America, residing at Louisville, in the county of Jefferson and State of Kentucky, have invented a new, original, and ornamental Design for a Combined Shawl and Head Covering, of which the following is a specification, reference being had to the accompanying drawing, forming a part thereof.

In the drawing:

I claim:

The ornamental design for a combined shawl and head covering, as shown.

RAYMOND M. WOLFE.
